APPARATUS FOR THE CONTROL OF
HIGHWAY CROSSING SIGNALSArba G. Williamson, Carnegie, Pa., assignor to
The Union Switch & Signal Company, Swiss-
vale, Pa., a corporation of Pennsylvania

Application August 1, 1933, Serial No. 683,164

14 Claims. (Cl. 246—130).

My invention relates to apparatus for the control of highway crossing signals, and particularly to apparatus controlled by a train approaching a highway for starting the operation of the highway signal in accordance with the speed of the train.

I am aware that control systems have heretofore been proposed wherein apparatus controlled by a train approaching a highway intersection determines the time of starting the operation of the highway crossing signal in accordance with the speed of the train. These control systems heretofore proposed require, as far as I am aware, a measuring track circuit and a plurality of operating track circuits which a train traverses successively as it approaches the intersection. Such arrangement of track circuits is expensive to install and greatly interferes with the track circuits of the train signaling system where such is in use. A feature of my present invention is the provision of novel and improved apparatus wherewith a train approaching a highway intersection governs the operation of the highway signal in accordance with the speed of a train without the necessity of such plurality of track circuits, and which apparatus is readily superposed on an existing track circuit. Other features and advantages of my invention will appear as the specification progresses.

30 I will describe certain forms of apparatus embodying my invention, and will then point out the novel features thereof in claims.

In accompanying drawings, Fig. 1 is a diagrammatic view of one form of apparatus which may be employed for carrying out the embodiment of my invention, and which form is adapted to control a motor driven cam circuit controller type of time measuring device. Fig. 2 is a diagrammatic view of a second form of apparatus embodying my invention, which form is adapted to control a time element relay type of time measuring device. Fig. 3 is a diagrammatic view of a third form of apparatus wherein the apparatus is superposed on a track circuit whose traffic rails are intersected by a highway at a point other than at the outgoing end of the track circuit, and which apparatus also embodies my invention. Figs. 4, 5 and 6 are views partly diagrammatical and partly sectional of a track rail contactor adaptable to be used with my invention.

In each of the several views, similar reference characters refer to similar parts.

Referring to Fig. 1, the reference characters 1 and 1^a designate the track rails of a stretch of railway over which traffic normally moves in the

direction indicated by the arrow and which are intersected by a highway H. In this form of my invention, the apparatus is superposed upon a track circuit designated by the reference character D—E which comprises the track rails to the left of the intersection, a track battery 2 connected across the traffic rails at one end, and a track relay TR having a winding 13 connected across the traffic rails at the other end of the circuit.

At the intersection there is provided a highway crossing signal S. The signal S is indicated on the drawing by a conventional symbol commonly used in the art to indicate a combined audible and visible signal in the form of an electric bell and a pair of flashing lights. It will be understood, however, that my invention is not limited to any specific form of highway crossing signal and any of the standard signals may be used.

The immediate control of the signal S is governed jointly by a relay K and a flasher relay NF. The relay K is a direct current neutral relay which is slightly slow releasing in character. The flasher relay NF may take different forms but preferably is similar to that disclosed in the United States Letters Patent, Reissue No. 17,252, to C. S. Snavely and W. B. Wells, for Electrical relays. In connection with the flasher relay NF, it is deemed sufficient for the present application to point out that the armature 4 is biased to a normal or central position, that is, to the position illustrated in Fig. 1, and is adapted to be attracted to the right or to the left by the energizing of windings 7 and 9, respectively. The armature 4 makes engagement with a contact 5 when it occupies its normal position and when it is swung to the right under the influence of the winding 7. When the armature 4 swings to the left under the influence of the winding 9, it breaks engagement with the contact 5 and makes engagement with a contact 8. Engagement of armature 4 with the contact 5 completes a short-circuiting connection on the winding 7 and engagement of armature 4 with the contact 8 completes a short-circuiting connection on the winding 9 as will be readily understood by an inspection of Fig. 1. When positive current is supplied to the wire 6 in a manner to be described hereinafter, the winding 7 will not at first be energized due to the short-circuiting connection but winding 9 will be energized and armature 4 will be attracted away from the contact 5 and into engagement with the contact 8. Winding 9 will now be deenergized due to the short-circuiting connection and winding 7 will receive current

with the result that armature 4 will be attracted back to the right into engagement with the contact 5. It follows that the windings 7 and 9 will be alternately energized causing armature 4 to swing back and forth between the contacts 5 and 8. The parts are so proportioned that the armature 4 will make a complete cycle of operation substantially every two seconds.

A circuit controlling contact 10 is operatively connected with the armature 4 as indicated by a dotted line. The circuit controlling contact 10 normally engages with two flexible spring contacts 11 and 12. The arrangement is such that when armature 4 swings to the right under the influence of winding 7, the circuit controlling contact 10 breaks engagement with the spring 12, and when armature 4 swings to the left under the influence of winding 9, the circuit controlling contact 10 breaks engagement with the spring 11. It follows that the circuit controlling contact 10 is operated by the armature 4 to alternately break engagement with the springs 11 and 12. The circuit controlling contact 10 governs the circuits for the signal lights 15 and 16 of the signal S in a manner to be pointed out hereinafter.

In order to clarify the following description, I shall assume the maximum speed for trains approaching the highway H to be 90 miles per hour and that 20 seconds operation of the signal S before a train reaches the intersection is required. A train travelling 90 miles per hour will move 2640 feet in 20 seconds. I shall further assume that the track circuit D-E is a circuit used in connection with a train signalling system and according to the usual practice is of the order of 5000 feet in length. The remaining distance of the track circuit over the 2640 feet required to assure 20 seconds operation of the signal S, I shall refer to in the following description as a distance X. For reasons to appear hereinafter, the track relay TR is preferably an interlocking relay of the well known type comprising two windings 13 and 14, the winding 13 receiving current from the track circuit D-E and the winding 14 receiving current from a track circuit E-F, including the traffic rails to the right of the intersection. It will be understood, however, that my invention is not limited to any specific layout of track circuit and may be superposed on various arrangements of track circuits, and also that the apparatus may be adjusted for different maximum speeds of trains, and different operating times of the highway crossing signal.

The relay K is normally energized over a stick circuit governed by the track relay TR and is provided with pickup and holding circuits controlled in part by a time measuring device designated as a whole by the reference character TM. The normal stick circuit can be traced from the positive terminal B of any convenient source of current such as a battery not shown over its own front contact 62, winding of relay K and front contact of the armature 53 of the track relay TR to the terminal C of the same source of current. Relay K may also normally receive current over a pickup circuit including the B terminal of the current source, contact 56-57 to be described later, winding of relay K and the front contact of armature 53 to the opposite C terminal of the current source. The function of this pickup circuit and the manner whereby the time measuring device TM controls the pickup and holding circuits for relay K will be pointed out later in the description.

The time measuring device TM may take dif-

ferent forms and preferably includes a shaft 19 shown schematically by a dotted line, and on which are rigidly mounted two circuit controlling cams 17 and 18 and a circuit controlling contactor 23. Shaft 19 is driven in either direction by a constant speed reversible motor M through the medium of a suitable gear train indicated by the reference character GT. The cams 17 and 18 and the contactor 23 normally occupy the position illustrated in the drawings, and are arranged to be moved away from this normal position in a clockwise direction toward a reverse position by rotating the motor M in one direction, the full reverse position preferably being substantially 300° or 5/6 of one revolution. At the full reverse position, the contactor 23 occupies the position indicated by the dotted line and opens a motor circuit as will later appear at the contact 28 to automatically stop operation of the motor M. At other times, shaft 19, cams 17 and 18 and the contactor 23 are restored to the normal position by rotating the motor M in the reverse direction, the contactor 23 opening the motor circuit at the contact 30 when the full normal position is reached.

The cam 18 is so positioned on the shaft 19 that its raised portion 55 registers with a contact spring 56 to raise that spring into engagement with a contact 57 only when the shaft 19 occupies its full normal position. The cam 17 is so positioned on the shaft 19 that its raised portion 58 registers with a contact spring 59 to lift that spring into engagement with a contact 60 when the cam has been rotated substantially 50° clockwise from the normal position, that is, one-sixth of the total movement. Once the contact 59-60 is closed, it is held closed until such time as the cam 17 is rotated back toward the normal position and the raised portion 58 moves away from beneath the spring 59.

The gear train GT of the time measuring device TM may take different forms and preferably is of the type disclosed in the United States Letters Patent, No. 1,991,756, granted February 19, 1935, to B. Lazich on Apparatus for changing speed and direction of rotation by reversing a constant speed motor, to which reference is made for a full description of this gear train. It is deemed sufficient for the present application to point out that when motor M is rotated in the direction to drive the shaft 19 clockwise, the gear reduction of the gear train GT is so proportioned that the shaft 19 is rotated at a rate sufficient to just bring the raised portion 58 of the cam 17 to the point where it registers with the spring 59 in the time interval required for a train travelling at the maximum speed of 90 miles per hour to pass over the distance X of the track circuit. At this speed, then, contact 59-60 will not close while the train is traversing distance X, but it will close while a train travelling at any lesser speed is traversing distance X. In other words, the gear reduction when the motor drives the shaft 19 clockwise is made such that cam 17 is rotated approximately 50° in the time required by a train travelling 90 miles per hour to pass over the distance X. If the train is travelling at a lesser speed, the cam 17 will be rotated some distance beyond the point where the contact 59-60 becomes closed during the time the train is passing over the distance X, the amount of the rotation of cam 17 being increased as the speed decreases. When the motor M is rotated in the direction to drive shaft 19 counter-clockwise, the gear reduction of the gear train GT is so propor-

tioned that the shaft 19 is rotated at such a rate that the full movement from the reverse position to the normal position is completed in approximately 120 seconds. Consequently, cam 17 is 5 rotated from the point where its raised portion 58 passes from beneath the spring 59 to the full normal position in approximately 20 seconds. That is to say, the gear reduction for driving shaft 19 clockwise is arranged in accordance with 10 the distance X of the track circuit and the maximum speed, and the gear reduction for driving shaft 19 counter-clockwise is arranged to make the complete movement in a predetermined time interval. The function of these gear ratios will 15 appear when the operation of the apparatus is described. The specific structure of this gear train GT, however, forms no part of my present invention, and is shown conventionally for the sake of simplicity.

20 The time measuring device TM also includes a direct current neutral relay L which is adapted to control the motor M in the following manner. When relay L is energized, an operating circuit is completed from the B terminal of the source 25 of current over front contact 24, armature 25 of motor M, contact 23-26, front contact 27, and field winding 28 to the opposite terminal C of the current source. The flow of current through the armature 25 is in a direction to cause the 30 motor M to rotate in the direction that drives the shaft 19 clockwise. When relay L is deenergized, an operating circuit is completed from the B terminal of the current source over back contact 29, contact 23-30 when shaft 19 has been 35 moved away from its normal position, armature 25, back contact 31, and the field winding 28 to the opposite battery terminal C. The flow of current through the armature 25 is reverse to that previously mentioned and the motor M rotates in a direction to rotate the shaft 19 counter-clockwise. It is clear from the foregoing that 40 energizing the relay L results in the circuit controlling cams 17 and 18 being rotated in the clockwise direction from the normal position toward the reverse position, and deenergizing the relay L reverses the movement and the cams 17 and 18 are rotated toward the normal position, the 45 movement being stopped when the full reverse and the full normal positions are reached by the 50 circuit controller 23.

C1 and C2 are track rail contactors which are operated from an engaging to a non-engaging position by the leading wheel of a train, and which are automatically restored to the engaging position when the train has vacated the track circuit. Referring to Figs. 4, 5 and 6, the casting 20 is adapted to be attached to the web of the traffic rail in any convenient manner. 21 is a rocker arm pivoted by a pin 22 having bearings in the casting 20 and an outer plate 99. The left-hand end of the rocker arm 21 is formed with an engaging surface 3 which is raised adjacent the rail head to a position to be engaged by the flange of a car wheel as it moves along 55 the rail. An eyebolt 32 is pinned to a jaw 33 at the left-hand end of the rocker arm 21 by a pin 34. A trunnion block 35 is carried by trunnion pins 36 journaled in the casting 20 and in the outer plate 99. The eyebolt 32 extends through 60 the trunnion block 35 and a spring 37 under compression is carried between the block 35 and a shoulder 38 of the eyebolt 32. It follows that when the rocker arm 21 is depressed to a point where the pin 34 passes below the center line 65 70 of the bearing pins 36, the spring 37 will force

the left-hand end of the rocker arm 21 still further downward until a stop 39 is reached. In the depressed position, the contact surface 3 is below engagement with the flange of the car wheels, that is to say, only the leading wheel of 5 a train operates the rocker arm 21.

A magnetic plunger 40 is pinned to the right-hand end of the rocker arm 21 by a pin 41, and is adapted to be drawn downward when a solenoid magnet 42 is energized. It is clear, 10 therefore, that energizing the magnet 42 subsequently to a car wheel depressing the rocker arm 21 in the manner pointed out above, draws the plunger 40 downward and raises the left-hand end of the rocker arm 21. When the pin 15 34 passes above the center line of the bearing pins 36, the toggle spring 37 will force the arm 21 still further upward to the engaging position, the movement being limited by a stop 43.

At the right-hand end of the rocker arm 21 is pinned a controller rod 44 of suitable material and into which are secured pins 45 and 46, the pins 45 and 46 carrying rollers 97 and 98, respectively. It follows that the controller rod 44 is raised to an upper position when the rocker 25 arm 21 is depressed and is lowered to a down position when the rocker arm 21 is restored to its engaging position. The rollers 97 and 98 engage two contact springs 47 and 48, respectively, the arrangement being such that with rod 44 in 30 its down position, the spring 47 breaks engagement with a mating spring 49 to open the contact therethrough, and the spring 48 makes engagement with a mating spring 50 to close the connection therethrough. When the rod 44 is 35 raised, the roller 97 lifts the spring 47 into engagement with the spring 49, and the roller 98 lifts the spring 48 out of engagement with the spring 50. Although a specific form of track rail contactor is here disclosed, it will be understood that I do not wish to limit myself to any specific structure of contactor, and the form here shown will serve to illustrate a contactor adaptable to my invention.

Referring again to Fig. 1, the track rail contactor C1 is preferably located 2640 feet to the left of the highway H, and the track rail contactor C2 is preferably located at substantially 400 feet to the left of the highway. The function of the position of these track rail contactors will 50 appear as the operation of the apparatus is described.

In describing the operation of the apparatus of Fig. 1, I shall assume that the apparatus occupies the position shown in the drawings and 55 that a train travelling in the normal direction of traffic approaches the intersection. As the leading wheels of the train enter the track circuit D-E, the winding 13 of the track relay TR will be deenergized and the armatures 51, 52, 53 and 60 54 controlled thereby will be released to their full down positions. Current will now flow from the positive terminal B of the current source through the winding of the relay L, back contact of armature 52 of the track relay TR, line wire 61, normally closed contact 48-50 of the track rail contactor C1 and thence to the C terminal of the current source, and relay L will be picked up. With relay L picked up, motor M will be operated 65 in a direction to rotate shaft 19, and the cams 70 17 and 18 clockwise away from the normal position. The stick circuit by which the relay K is normally held energized and which includes the front contact of armature 53 of the track relay TR will now be open, and that relay will be re- 75

leased unless some other means is provided for supplying its winding with current. The picking up of the relay L completes a holding circuit for the relay K by which current will flow from the B terminal of the current source over the front contact 62 of relay K, winding of that relay, front contact 63 of relay L, back contact of armature 52 of relay TR, line wire 61, and the normally closed contact 48-50 of the contactor C1 to the opposite C terminal of the current source. Consequently, the relay K will be retained energized after the train enters the track circuit D-E, providing the relay L is picked up to start operation of the timing device TM, and the contactor C1 has not yet opened contact 48-50.

Motor M operated in response to the picking up of relay L causes the cams 17 and 18 to be rotated in the clockwise direction until the train advances to the point where its leading wheel depresses the contactor C1 and opens the contact 48-50 which is included in the energizing circuit for relay L, and also in the holding circuit for relay K. Relay L will now be deenergized and the motor M will be reversed in its operation with the result that the cams 17 and 18 will be rotated counter-clockwise from the position to which they had advanced back to the normal position. As stated above, the holding circuit for the relay K is also opened at the contact 48-50 of the contactor C1, but that relay may now be supplied with current over another holding circuit extending from the B terminal of the current source over front contact 62, winding of the relay, contact 59-60 providing the cam 17 has been rotated clockwise far enough to bring its raised portion 58 under the spring 59, back contact 64 of the relay L, normally closed contact 48-50 of the contactor C2, and thence to the C terminal of the current source.

As set forth hereinbefore, the gear reduction through which the motor M operates the shaft 19 in a clockwise direction is so proportioned with respect to the distance X of the track circuit D-E that in the event the train is travelling at the maximum speed of 90 miles per hour, the cam 17 will not have been rotated to the point where its raised portion 58 will lift the spring 59 into engagement with the contact 60. Hence, it is clear that in the event the train approaching the intersection is travelling at the maximum speed of 90 miles per hour, the last traced holding circuit for the relay K, and which includes the contact 59-60, will not be closed and relay K will be released to start operation of the highway crossing signal S. Relay K, upon releasing, closes a back contact 93 and current will flow from the B terminal of the current source over the back contact of armature 54 of the track relay TR, back contact 93 of the relay K, wire 6, windings 7 and 8 of the flasher relay NF, and to the C terminal of the current source, and relay NF will be operated in the manner described hereinbefore. Current will also flow over this same circuit up to the wire 6 and thence over the springs 11 and 12 alternately to the lamps 15 and 16 of the signal S and thence to the C battery terminal, to flash these lamps in step with the operation of the flasher relay NF. Furthermore, current will pass from the wire 6 through the winding of the bell 94 of the signal S, and thence to the C terminal of the current source to sound the bell. The result would be that the signal S will be operated from the time the leading wheel of the train engages the con-

tactor C1 and a full 20 seconds operation before the train travelling 90 miles per hour reaches the highway will be assured.

A train travelling 30 miles per hour over the distance X of the track circuit D-E will take an interval three times as long as the train travelling 90 miles per hour and will consume a time interval great enough so that the cam 17 will be rotated substantially 150° away from the normal position, the contact 59-60 being closed during the last 100° of that movement. When the leading wheel of this train engages the contactor C1 and causes reverse operation of the motor M of the timing device TM, the holding circuit for the relay K including the contact 59-60 will be closed and that relay will be retained energized. If the full 300° movement from reverse to normal requires 120 seconds, it will require substantially 60 seconds of operation of the motor M in the reverse direction to rotate the cam 17 from the 150° position back to its normal position. Hence, contacts 59-60 will be held closed during the first 40 seconds of that 60 second period with the result that the relay K will not be released and the signal S will not be operated until this train has advanced for 40 seconds to the right of contactor C1. A train travelling 30 miles per hour will require 60 seconds in travelling 2640 feet, and hence it follows that 20 seconds operation of the signal S will be obtained before this train travelling 30 miles per hour reaches the highway H.

The time measuring device TM will function in a similar manner for trains of other speeds with the result that substantially 20 seconds operation is assured for the signal S regardless of the speed of the train. In any event, a train advancing to the track rail contactor C2 will operate that contactor and open its normally closed contact 48-50. The holding circuit for the relay K which includes the contact 59-60 of cam 17 also includes the contact 48-50 of the contactor C2, and hence positive operation of the signal S when a train reaches the contactor C2 is assured. That is to say, the distance from the contactor C2 to the highway H forms a positive operating section.

Track rail contactors C1 and C2 when depressed each closes the respective contact 47-49, and, consequently, when the rear of the train vacates the track section D-E, and the winding 13 of the track relay TR is reenergized, current will flow from the B terminal of the current source over front contact of the armature 51 of relay TR, wire 65, magnet 42 of the contactor C2, the associated contact 47-49 and to the opposite terminal C of the current source, and magnet 42 of contactor C2 will be energized. Magnet 42 when energized restores the contactor C2 to its engaging position and the associated contact 47-49 will be opened in the manner described hereinbefore. Current will also flow over this same circuit up to the wire 65 and thence over wire 66, magnet 42 of the contactor C1 and its associated contact 47-49 to the opposite terminal C of the current source, and the contactor C1 will be restored to its engaging position in the same manner just described for contactor C2.

After the train has vacated the track circuit D-E and winding 13 of relay TR is reenergized and the time measuring device TM has been operated back to its full normal position, current will flow over the pickup circuit including the B terminal of the current source, contact 56-57 of the cam 18, winding of the relay K, front con-

tact of armature 53 of relay TR and to the opposite terminal C of the current source, and relay K will be picked up to stop operation of the flasher relay NF and of the signal S. It is to be noted 5 that in the event a second and following train should enter the track circuit D—E before the first train clears the highway H, the contactors C1 and C2 both will remain in the non-engaging position and the relay K will remain deenergized 10 with the result that operation of the signal S will be continued until the following train has cleared the highway H.

A train moving against the normal direction of traffic will deenergize the winding 14 of the relay 15 TR previous to the shunting of the winding 13. The interlocking feature usually provided between the armatures controlled by the winding 14 and the armatures controlled by the winding 13 will prevent the full release of the armatures controlled 20 by the winding 13 and the relay NF and signal S will not be operated by this train moving against traffic. The leading wheel of the train moving against traffic will cause operation of the contactors C2 and C1 and once depressed 25 these contactors will remain in the non-engaging position inasmuch as the front contact of armature 51 of the track relay TR will be open, but when the rear of the train vacates the track circuit D—E, the winding 13 will be reenergized, 30 and contactors C1 and C2 will be automatically restored to their engaging positions.

Referring now to Fig. 2, the traffic rails 1 and 1^a are intersected by a highway H and are provided with a track circuit D—E the same is in Fig. 1. 35 Relay K and the flasher relay NF jointly control the operation of signal S in the same manner as in Fig. 1. Relay K is also provided with pickup and stick circuits similar to those of Fig. 1 as will shortly appear.

40 In this form of my invention, the time measuring device TM1 is of the time element relay type which may take different forms but a preferred form is that fully disclosed in the Letters Patent of the United States, No. 1,966,965, granted July 17, 1934, to B. Lazich and H. E. Ashworth, for Electrical relays. It is deemed sufficient for the present application to say that with the operating winding 67 of device TM1 energized, an armature 68 is oscillated back and forth at a pre-determined rate to actuate a pawl 69 and drive a ratchet 70 in the clockwise direction. Ratchet 70 operates a segment 71 through a planetary gear. With a clutch winding 72 energized, oscillations of armature 68 are stopped and a clutch 55 73 is actuated by an armature 74 as indicated by a dotted line to engage and hold stationary the segment 71. Circuit controlling contacts 75, 76 and 80 are operatively connected with the segment 71 as indicated by a dotted line, and hence 60 are operated from a normal position illustrated by the full lines in the drawings to a reverse position illustrated by the dotted lines, the movement of circuit controlling contacts 75, 76 and 80 being completed in a predetermined time interval. 65 For reasons to appear hereinafter, the parts are so proportioned that the contacts 75, 76 and 80 are operated from the normal position to the full reverse position in the time interval required for a train travelling, say, for example, 55 miles 70 per hour to pass over the distance X of the track circuit D—E. The clutch winding 72, when de-energized, permits the segment 71 to fall back under the force of gravity to its normal position operating the controller contacts 75, 76 and 80 75 back to the full normal position. A check con-

tact 81—82 is provided to check the normal position of segment 71, the contact spring 81 being lifted into engagement with the contact spring 82 through the medium of a member 83 attached to the segment 71, and the arrangement being such that the contact 81—82 is closed only when the segment 71 is in its full normal position as illustrated in the drawings.

Circuit controlling contact 75 makes engagement with a contact segment 77 from its full normal position until just before the full reverse position is reached. Circuit controlling contacts 76 and 80 make engagement with contacts 78 and 84, respectively, only in the full reverse position.

Track rail contactors C1 and C2 of Fig. 2 are similar in all respects to the corresponding contactors of Fig. 1, and contactor C1 is located 20 2640 feet from the intersection. In this form of my invention, the contactor C2 is preferably located at a point which I shall assume to be 1600 feet from the highway. It will be understood, of course, that the contactors C1 and C2 may be set down along the traffic rails at other distances from the intersection should it seem 25 desirable to do so.

I shall now describe the operation of the apparatus of Fig. 2. A train approaching the intersection in the normal direction of traffic and entering the track circuit D—E will shunt the 30 winding 13 of the track relay TR and the associated armatures will be released to their full down positions. Current will now flow from the B terminal of the current source through the operating winding 67 of the time measuring device 35 TM1, back contact of armature 52 of the track relay TR, line wire 79, and the normally closed contact 48—50 of the contactor C1 to the opposite terminal C of the current source, and the time measuring device TM1 will be set into operation. The normal stick circuit for the relay K will be opened at the front contact of armature 53 of relay TR as the train enters the track section D—E, but said relay K will now be supplied with current over a holding circuit that 45 includes its own front contact 62, winding of relay K, contact 75—77, back contact of armature 52 of relay TR, wire 79, and the normally closed contact 48—50 of the track relay contactor C1 to the C battery terminal. When the train has advanced to the location of the contactor C1, its leading wheel will depress the contactor to its non-engaging position to open the contact 48—50 and current will be removed from the operating winding 67 of the time measuring device 50 TM1, and also from the winding of the relay K. In the event the train is travelling at a speed above 55 miles per hour and the segment 71 has not been advanced far enough to bring the circuit 55 controlling contacts 75, 76 and 80 to their reverse positions before the operating winding 67 is deenergized, the segment 71 immediately falls back to its normal position. Relay K will now be without current and its back contact 93 will be closed to cause operation of the flasher relay NF and, in turn, operation of the signal S in the same manner as described in connection with the apparatus of Fig. 1. In the event the speed of the train is below 55 miles per hour and the segment 71 has been operated to bring the circuit 60 controlling contacts 75, 76 and 80 to the full reverse position before the track rail contactor C1 is actuated by the leading wheel of the train, current will flow from the B terminal of the current source through the clutch winding 72, con- 65

tact 80—84, and contact 48—50 of the contactor C2 to the opposite terminal C of the current source, and the segment 71 will be held in the full reverse position. Relay K will now receive current over another holding circuit that includes its own front contact 62, winding of this relay, contact 76—78 of the time measuring device TM1, and the contact 48—50 of the contactor C2 to the C battery terminal. Under this condition, operation of the track rail contactor C1 will not result in starting the operation of the signal S.

When this train travelling less than 55 miles per hour reaches the location of the contactor C2, and operates that contactor to open the associated contact 48—50, current will be removed from the clutch winding 72 of the time measuring device TM1 and also from the winding of the relay K. Relay K will now be without current 20 and the signal S will be set into operation. When a train has passed beyond the highway H and vacated the track circuit D—E of Fig. 2, current will be supplied to the operating magnet 42 of each of the track rail contactors C1 and C2 over 25 the front contact of armature 51 of the track relay TR, and these contactors will be restored to their normal engaging positions in the same manner as described in Fig. 1. As the train vacates the track circuit D—E, the relay K will be 30 supplied with current over a pickup circuit which includes the B terminal of the current source, check contact 81—82, winding of that relay, and the front contact of armature 53 of the relay TR to the opposite terminal C of the current 35 source. Consequently, relay K will be picked up and operation of the signal S stopped when the rear of the train has passed beyond the highway H providing the time measuring device has also assumed its normal position.

40 It follows that for trains having speeds above 55 miles per hour, the signal S will be set into operation when the train reaches the location of the more remote track rail contactor C1, and which is located far enough from the highway so 45 that at least 20 seconds operation of the signal before the train reaches the highway is assured even for the maximum speed of 90 miles per hour. For trains travelling at a speed less than 55 miles per hour, the operation of the signal S is delayed 50 until the train reaches the location of the second track rail contactor C2, and which location is a sufficient distance from the highway that at least 20 seconds operation of the signal before these trains reach the highway is assured.

55 In Fig. 3, the traffic rails 1 and 1^a are intersected by the highway H at a point some distance from the outgoing end of the track circuit D—E. At the intersection, there is provided in the rail 1^a an insulated rail joint 85 around which is connected the winding of a relay R so that the winding of this relay is serially connected into the track circuit. The relay R is so proportioned and adjusted that the energization resulting from the normal track circuit current is sufficient to 60 lift the armature of that relay out of engagement with the back contacts and into engagement with the front contacts. The track rail contactors C1 and C2 and the time measuring device TM1 are preferably similar to the corresponding devices of 65 Fig. 2, and the contactors C1 and C2 are located with respect to the highway H as in Fig. 2. The highway crossing signal S1 of Fig. 3 is shown as an audible signal in the form of an electric bell, the operating circuit of which is controlled by an 70 interlocking relay K1.

The circuits and the operation of the apparatus of Fig. 3 can best be described simultaneously. Normally the apparatus occupies the position illustrated in the drawings and both windings 86 and 87 of the relay K1 are supplied with current 5 and the signal S1 is silent, the winding 86 being controlled over a stick circuit including its own front contact 89 and the front contact 90 of relay R, and winding 87 being controlled over front contact 94 of relay TR1. A train travelling in the 10 normal direction of traffic and approaching the intersection will shunt the track circuit D—E and both relays R and TR1 will be deenergized. Current will now flow from the B terminal of the current source over back contact 88 of relay R, operating winding 67 of the time measuring device 15 TM1 and the normally closed contact 48—50 of the contactor C1 to the opposite battery terminal C, and the device TM1 will be set into operation. The winding 86 of the relay K1, which normally 20 received current over the stick circuit including front contact 90 of relay R will, upon the deenergizing of the relay R, receive current over a holding circuit extending from the B terminal of the current source, front contact 89, winding 86, back 25 contact 94 of the relay R, contact 75—77 of the time measuring device TM1, and the contact 48—50 of the contactor C1 to the C battery terminal. Thus it follows that winding 86 remains energized and the signal S1 remains silent after the 30 train enters the track circuit. It will be noted that winding 87 of relay K1 will now receive current over the back contact 95 of relay R and its own front contact 96. In the event the train is travelling at a speed above a predetermined 35 value, say 55 miles per hour, it will pass over the portion X of the track circuit D—E, and its leading wheel will actuate the track rail contactor C1 before the time measuring device TM1 has been operated long enough to close the contacts 76—78 40 and 80—84, and hence operation of the device TM1 will be stopped and the winding 86 of the relay K1 will be deenergized. The full-down contact 92 of the relay K1 will now be closed and current will be supplied to the operating circuit 45 easily traced for the signal S1, and the signal set into operation. In the event the train is travelling at a speed less than 55 miles per hour the device TM1 will be operated to close its contacts 76—78 and 80—84 before the contactor C1 is actuated, and the clutch winding 72 of the device TM1 will receive current over the back contact 88 50 of relay R, contact 80—84 of device TM1 and the normally closed contact 48—50 of the track rail contactor C2; and the time measuring device will 55 be held in its reverse position. The winding 86 of the relay K1 will now receive current over its own front contact 89, winding 86, back contact 91 of relay R, contact 76—78 of device TM1 and the contact 48—50 of the contactor C2, and hence, 60 the signal S1 will remain silent. When the train moves on closer to the intersection and actuates the contactor C2, the opening of its contact 48—50 will deprive both the clutch winding 72 of the device TM1 and the winding 86 of the relay K1 of 65 current, and they will both be deenergized. The device TM1 will now assume its normal position, and the full-down contact 92 of relay K1 will be closed with the result that the signal S1 will be 70 set into operation.

When the rear of a train passes the insulating rail joint 85, the relay R will be picked up by the current flowing through the train shunt and current will flow from the B battery terminal over the check contact 81—82 of the device TM1, wind- 75

ing 86 of relay K1 and front contact 90 of the relay R to the opposite battery terminal C, and winding 86 will be energized to open the back contact 92, and the operation of the signal S1 will be stopped. When the train vacates the track circuit D—E and the relay TR1 is reenergized, the track rail contactors C1 and C2 will each be restored to its normal engaging position over the circuit including the front contact 93 of the relay 10 TR1, the manner of restoring these contactors being similar to that already described in connection with Figs. 1 and 2.

A train moving against the normal direction of traffic and entering the track circuit D—E will 15 shunt the track relay TR1, but the relay R will remain energized until the head end of the train has advanced to the left of the insulated rail joint 85. Under this condition, the winding 87 of the relay K1 will be deprived of current inasmuch as both the front contact 94 of relay TR1 and the back contact 95 of relay R are open at the same time. Winding 87 once deenergized, it will not be reenergized until the train has vacated the circuit D—E and the track relay TR1 is picked 20 up. Winding 87 being deenergized previous to the deenergizing of winding 86, the interlocking feature between the armatures of these windings will prevent the full-down contact 92 from becoming closed and the signal S1 will not be operated 25 by the train moving against traffic. It is to be seen from the foregoing description that the signal S1 is set into operation at the location of the more remote contactor C1 for trains travelling above 55 miles per hour, and that its operation is delayed until the train reaches the nearer contactor C2 when the speed of the train is below 30 55 miles per hour. Operation of the signal S1 is stopped as soon as the rear of the train passes the highway, and is not operated by a train moving 35 against traffic. The track rail contactors C1 and C2 are restored to their normal engaging positions automatically in response to a train vacating the track circuit travelling in either direction. The normal position of the contactors and also 40 the normal position of the time measuring device TM1 is checked. Although a time element relay type of time measuring device is disclosed for the apparatus of Fig. 3, it is clear that a time measuring device of the type disclosed in Fig. 1 may be 45 employed should it seem desirable to do so.

Apparatus such as here disclosed governs the 50 operation of a highway crossing signal in accordance with the speed of a train approaching the intersection, and is adaptable to be superimposed upon an existing track circuit irrespective of the point at which the highway intersects the traffic rails without subdivision of the track circuit.

Although I have herein shown and described 55 only certain forms of apparatus embodying my invention, it is understood that various changes and modifications may be made therein within the scope of the appended claims without departing from the spirit and scope of my invention.

Having thus described my invention, what I 60 claim is:

1. In combination, a stretch of railway track 65 intersected by a highway, a highway crossing signal located at the intersection, a track rail contactor located at a fixed point which a train passes in approaching the highway and which contactor includes a member adapted to be depressed from an engaging position to a non-engaging position by a wheel of the train, means for retaining said member in the non-engaging 70 position, operating means controlled by said

member when depressed for setting said signal into operation, time measuring means, means controlled by the train moving over a given distance in approaching said track rail contactor for operating said time measuring means, means controlled by said time measuring means for delaying the operating means from setting said signal into operation in accordance with the measured time, and means controlled by the train moving away from the intersection for restoring 10 the member of said contactor to the engaging position.

2. In combination, a stretch of railway track intersected by a highway, a highway crossing signal located at the intersection, a track rail contactor located a given distance from the intersection and including a member adapted to be depressed from an engaging position to a non-engaging position by a wheel of the train, means for retaining said member in the non-engaging 15 position, operating means controlled by said member when depressed for setting said signal into operation, speed measuring means controlled by the train approaching said track rail contactor for determining the speed of the train, 20 means controlled by said speed measuring means for at times delaying the operating means from setting said signal into operation, and means controlled by the train moving away from said intersection for restoring said member of the 25 track rail contactor to its engaging position.

3. In combination, a stretch of railway track intersected by a highway, a highway crossing signal located at the intersection, a track rail contactor located a given distance from the 30 intersection and including a member adapted to be actuated from a first position to a second position by a wheel of a train, means for retaining said member in said second position, operating means controlled by said member in said second 35 position for setting said signal into operation, speed measuring means controlled by the train approaching said track rail contactor for determining the speed of the train, means controlled by the speed measuring means for delaying the 40 operating means from setting said signal into operation in accordance with the measured speed, and means controlled by the train moving away from said intersection for restoring said member of the 45 track rail contactor to said first position.

4. In combination, a stretch of railway track 50 over which traffic normally moves in a given direction and which is intersected by a highway, a highway crossing signal located at the intersection, a track circuit including the track rails of the 55 stretch, a track rail contactor located adjacent one of said rails at a fixed point in advance of the entrance of said track circuit and which includes a member adapted to be actuated from a first 60 position to a second position by the leading wheel of a train and having means for retaining said member in said second position, a time measuring device, means controlled by said track circuit effective to render said time measuring device active in response to a train entering the track circuit, and operating means controlled jointly by 65 said member and said time measuring device for setting said signal into operation.

5. In combination, a stretch of railway track 70 over which traffic normally moves in a given direction and which is intersected by a highway, a highway crossing signal, located at the intersection, a track circuit including the track rails of the stretch, a track rail contactor including a member positioned adjacent one of said rails to 75

be engaged by a car wheel moving along the rail and actuated to a non-engaging position and having means for retaining said member in the non-engaging position, said contactor located in advance of the entrance of the track circuit and at a given distance from the intersection, a time measuring device including a motor element and a circuit controlling element actuated by said motor element, means controlled by the track circuit to set said motor element into operation in response to a train entering the track circuit, operating means controlled jointly by said member and said circuit controlling element for setting said signal into operation, and means controlled by the track circuit for restoring said member to its engaging position in response to the train clearing said track circuit.

6. In combination, a stretch of railway track over which traffic normally moves in a given direction and which is intersected by a highway, a highway crossing signal located at the intersection, a track circuit including the track rails of the stretch, a track rail contactor including a member positioned adjacent one of said rails to be engaged by a car wheel moving along the rail and actuated to a non-engaging position and having means for retaining said member in the non-engaging position, said contactor located in advance of the entrance of the track circuit and at a given distance from the intersection, a time measuring device including a circuit controlling element having a normal position and a motor element adapted to move said circuit controller element away from said normal position at a predetermined rate, means controlled by the track circuit to set said motor element into operation in response to a train entering the track circuit, means controlled by said member when actuated to govern said motor element and effective to arrest the movement of the circuit controlling element away from the normal position, operating means controlled by said member when actuated to start operation of the signal, means controlled by said circuit controlling element effective to delay the operating means in starting operation of the signal in accordance with the distance the circuit controlling element is moved away from the normal position, and means controlled by said track circuit effective to restore said member to its engaging position in response to the train vacating the track circuit.

7. In combination, a stretch of railway track over which traffic normally moves in a given direction and which is intersected by a highway, a highway crossing signal located at the intersection, a track circuit including the track rails of the stretch, a track rail contactor including a member adjacent one of said rails in a position to be engaged by a car wheel moving along the rail and actuated to a non-engaging position, said contactor located in advance of the entrance of said track circuit and at a given distance from the intersection, a circuit controller operated by said member and including a contact normally closed, operating means controlled by the track circuit for setting said signal into operation in response to a train entering the track circuit, circuit means including said normally closed contact for rendering said operating means ineffective to set said signal into operation whereby operation of said signal is delayed until said member is actuated by the leading wheel of the train, means for retaining said member in the non-engaging position, and means controlled by said track circuit for restoring said member to its

engaging position in response to the train vacating the track circuit.

8. In combination, a stretch of railway track intersected by a highway, a highway crossing signal located at the intersection, a first and a second track rail contactor each including a member positioned adjacent a traffic rail to be engaged by a car wheel moving along the rail and actuated to a non-engaging position and each having an element adapted to retain the member in the non-engaging position, said contactors located along the stretch and arranged to be successively passed by a train approaching the intersection, a time measuring device including a circuit controlling element, means controlled by a train approaching the more remote contactor for actuating said time measuring device, operating means controlled by the member of the more remote contactor when actuated for setting said signal into operation, circuit means including the circuit controlling element of the time measuring means effective to delay at times the operating means in setting said signal into operation, means controlled by the member of the contactor nearer the highway when actuated for rendering said circuit means ineffective, and means controlled by the train effective to restore the member of said contactors to their engaging positions when the rear of the train clears the highway.

9. In combination, a stretch of railway track intersected by a highway, a highway crossing signal located at the intersection, a first and a second track rail contactor each including a member positioned adjacent a traffic rail to be engaged by a car wheel moving along the rail and actuated to a non-engaging position and each having an element adapted to retain the member in the non-engaging position, said contactors located along the stretch and arranged to be successively passed by a train approaching the intersection, a time measuring device including a magnet and a contact adapted to be closed a predetermined time after said magnet is energized, means controlled by a train approaching the more remote contactor for energizing said magnet, means controlled by said member of the more remote contactor when actuated to deenergize said magnet, operating means controlled by said member of the more remote contactor when actuated for setting said signal into operation, circuit means including the contact of the time measuring device and effective when said contact is closed to render the operating means ineffective to set the signal into operation, means controlled by the member of the contactor nearer the highway when actuated to remove the control of said circuit means over the operating means, and means controlled by the train to restore the members of said contactors to their engaging positions rendered effective when the rear of the train clears the highway.

10. In combination, a stretch of railway track intersected by a highway, a highway crossing signal located at the intersection, a track rail contactor including a member positioned adjacent a traffic rail to be engaged by a car wheel moving along the rail and actuated to a non-engaging position and having an element adapted to retain said member in the non-engaging position, said contactor located a given distance from the intersection, a time measuring device including a member movable in opposite directions from and toward an initial position by a reversible motor, a contact actuated by said member during a predetermined portion of its movement, means con-

trolled by a train for operating said motor in a direction to move the member away from the initial position during the time the train is travelling a fixed distance in approaching said contactor, means controlled by said member of the contactor when actuated for reversing the operation of the motor, operating means controlled by said member of the contactor when actuated for setting said signal into operation, circuit means including said contact effective when said contact is closed to render the operating means ineffective to operate the signal, and means controlled by the train to restore the member of said contactor to its engaging position rendered effective after the rear of the train clears the highway.

11. In combination, a stretch of railway track over which traffic normally moves in a given direction, a track circuit including the track rails of said stretch and arranged with the source of current at the entrance of said circuit, a highway intersecting the stretch at an intermediate point of the track circuit, a highway crossing signal located at the intersection, an insulated rail joint located in one rail at the intersection, a relay having its winding connected around said insulated joint, a track rail contactor located along the stretch a given distance from the intersection and including a member adapted to be actuated by a car wheel moving along the rail, operating means controlled by said member when actuated for setting said signal into operation, and circuit means including a front contact of said relay for rendering said operating means ineffective whereby operation of said signal is stopped as the rear of a train clears the highway.

12. In combination, a stretch of railway track intersected by a highway, a highway crossing signal located at the intersection, a track circuit including the track rails of the stretch, a train actuated device attached to at least one rail at a fixed point in advance of the entrance of said track circuit and including an element responsive to the front end of a train passing said point, a time measuring device, means controlled by said track circuit effective to render said

time measuring device active in response to a train entering the track circuit, operating means controlled by said element for setting said signal into operation in response to a train passing said point, and means controlled by said time measuring means for at times delaying the operating means in setting said signal into operation.

13. In combination, a stretch of railway track intersected by a highway, a highway crossing signal located at the intersection, a track circuit including the track rails of the stretch, a train actuated device adjacent the track rails at a fixed point in advance of the entrance of said track circuit and including an element responsive to the front end of a train passing said point, a time measuring device, means controlled by said track circuit effective to render said time measuring device active in response to a train entering said track circuit, operating means controlled by said element for setting said signal into operation in response to a train passing said point, and means controlled by said time measuring device for at times delaying the operating means in setting said signal into operation.

14. In combination, a stretch of railway track over which traffic normally moves in a given direction, a track circuit including the track rails of said stretch and arranged with the source of current at the entrance of said circuit, a highway intersecting the stretch at an intermediate point of the track circuit, a highway crossing signal located at the intersection, an insulated rail joint located in one rail at the intersection, a track relay having its winding connected around said insulated joint, a train actuated device located adjacent the track rails at a fixed point in advance of the entrance of the section and including an element responsive to the front end of a train passing said fixed point, a control relay, means controlled by said relay when deenergized to set said signal into operation, a first energizing circuit for said control relay including a front contact of said track relay, and a second energizing circuit for said control relay including the element of said train actuated device.

ARBA G. WILLIAMSON.
